Primary Examiner — George A Bugg*Assistant Examiner* — Tamara L Hahn(74) *Attorney, Agent, or Firm* — K&L Gates(57) **CLAIM**

The ornamental design for a pallet, as shown.

DESCRIPTION

FIG. 1 is a perspective view of a pallet showing our new design.

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines show portions of a pallet that form no part of the claimed design. The dot-dash broken lines indicate the bounds of the claim and form no part of the claimed design.
